UNITED STATES PATENT OFFICE.

SAMUEL A. STUM, OF PROVO, UTAH.

BURNER.

Application filed June 3, 1926. Serial No. 113,495.

This invention relates to a burner for utilizing gas as a fuel and adapted for use in all kinds of heaters such as portable heaters, steam and hot water boilers, etc.

One of the objects of the invention is to provide a burner which does not require the use of screens or small holes such as has heretofore been used and which soon become clogged.

10 A further object is to provide a burner which requires no adjustment, and regardless of the pressure or quality of gas used, will not back-fire.

15 A further object is to provide burners utilizing opposed orifices disposed in pairs whereby the jets of flame issuing from the orifices of each pair will meet to effect a thorough mixing and consumption of the combustible gases, these orifices being so 20 disposed as to prevent unconsumed condensed fuel from running into and downwardly within the burners.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings the preferred forms of the invention have been 35 shown.

In said drawing,

Figure 1 is a plan view of a manifold having one arrangement of burners mounted thereon.

40 Figure 2 is a section on line 2—2, Figure 1.

Figure 3 is a section through a modified form of burner.

45 Referring to the figures by characters of reference 1 designates a manifold which, in the structure illustrated in Figures 1 and 2 includes parallel pipes connected to a supply pipe 3 so that a combustible gas delivered from the pipe 2 will be distributed to all portions of the manifold. Obviously, however, if desired the manifold can be of other shapes. For example it can be in the form of a straight pipe.

50 In the structure illustrated in Figures 1 and 2 each of the parallel portions of the

manifold is provided at desired points with apertures 3 in which are seated the lower threaded ends of brass nipples 4. The upper portions of these nipples are provided with long tapers as at 5 merging into abruptly tapered ends 6 in which are provided small orifices 7. A burner tube 8 having a slightly flared lower end 9 is fitted snugly upon the tapered portion 5 of each nipple 60 and is held against rotation thereon by means of a set screw 10. Formed in the tubular burner 8 adjacent the upper end of the nipple therein are air holes 11 and overhanging these air holes is a downwardly flared apron 12 extending continuously 70 around the burner tube. The upper end of the burner tube has an inclined tubular extension or offset 13 the end of which is vertically disposed as at 14 and is preferably 75 beveled inwardly as shown at 15. Where burners are used with a manifold as shown in Figures 1 and 2 they are arranged in pairs, one burner of each pair being directly 80 opposite the burner thereof with the upper inclined portions converging. Thus a jet of flame issuing from the upper portion of each burner will meet the jet of flame issuing from the other burner, these two jets meeting at a point midway between the two 85 burners so that a thorough mixing of the flames will result in complete combustion.

In practice it has been found that the air admitted to each burner through the holes 11 will produce a blue flame while the 90 secondary air which mixes with the flame at the outer end of the burner will change the flame to a hot orange-green.

Where the burners are mounted on a single pipe constituting a manifold they 95 will be arranged in pairs along the pipe, the burners of each pair having their upper ends converging upwardly. Such an arrangement is so obvious that a detailed description or illustration thereof is not 100 deemed necessary.

Each burner can be of the modified construction illustrated in Figure 3. In this form of device the nipple 16 extending from the pipe or manifold 17 is seated in the 105 slightly flared lower end portion of the burner tube 18 which has air holes 19 overhung by a flared apron 20. This tube is held against rotation by a set screw 21. These various parts are similar to the corresponding parts of the tube heretofore described. The modified structure differs from the first 110

described device, however, in that the upper portion of the tube is forked to provide tubular arms 22 diverging upwardly and then curved inwardly toward each other as shown at 23. The outlets 24 in these two arms are directly opposite each other and the passages within the arms are so positioned that the jets of flame issuing from the arms will flow toward each other along upwardly converging lines and meet at a point midway between the ends of the arms where a thorough mixing of the flame with the secondary air is effected. These burners can all be made of different sizes to meet the conditions under which they are to be used and the same can also be said of the burners illustrated in Figures 1 and 2.

As the various burner tubes are vertically disposed they can be used to advantage in large water or steam boilers wherein the primary air can be controlled by extending the burner tubes through sheets of asbestos or the like located upon the lower portions of the tubes close to but above the air holes. 11. A portion of such a sheet has been indicated by broken lines at 25 in Figure 2. By utilizing a sheet of this type there is no danger of the primary air chilling the boiler and thus reducing the efficiency of the burner.

Obviously any good thermostat can be used with these burners for the purpose of controlling the ignition of the burners from a pilot which can be centrally located. It is not thought that illustration or detailed description of this is necessary.

The hoods located above and around the air holes in the burners serve to prevent condensed fuel or the like from entering the air holes and interfering with the flow of gas through the orifices 7. Furthermore by providing the outlet ends of the burner tubes in vertical plane, condensed fuel is prevented from entering the tubes at their upper ends.

It has been found in practice that the burner such as herein described is very efficient for producing the maximum heat. Furthermore the consumption of fuel in proportion to the heat produced is reduced to the minimum. The burner can be used wherever gas is to be employed as a fuel. For example it can be used in cooking ranges, steam tables, large and small water heaters and steam boilers, in heating furnaces, etc.

What is claimed is:

1. In a gas burner the combination with a manifold and nipples communicating

therewith and extending upwardly therefrom, said nipples being tapered and having orifices in their upper ends, of burner tubes frictionally engaging and supported by the tapered nipples having air holes adjacent the upper ends of the nipples, means carried by the tubes and engaging the nipples for holding the tubes against rotation, an apron extending around each tube and the air holes therein for deflecting moisture from the openings, the upper ends of the tubes being arranged in pairs for directing jets of flame upwardly along converging lines to meet and mix at points between said ends, the outlet openings in the ends of the tubes being disposed in vertical plane.

2. In a gas burner the combination with a manifold and an upwardly tapered nipple thereon having an orifice, of a burner tube frictionally engaging and supported by the tapered nipple having air holes adjacent the upper end of the nipple, tubular arms diverging from the upper portion of the tube and having their upper end portions inturned and oppositely disposed for directing jets of fuel upwardly and inwardly along converging lines.

3. In a gas burner the combination with a manifold and an upwardly tapered nipple thereon having an orifice, of a burner tube frictionally engaging and supported by the tapered nipple having air holes adjacent the upper end of the nipple, tubular arms diverging from the upper portion of the tube and having their upper end portions inturned and oppositely disposed for directing jets of fuel upwardly and inwardly along converging lines, the outlet openings of the arms being disposed in parallel vertical plane and flared outwardly.

4. In a gas burner the combination with a manifold and an upwardly tapered nipple thereon having an orifice, of a burner tube frictionally engaging and supported by the tapered nipple having air holes adjacent the upper end of the nipple, tubular arms diverging from the upper portion of the tube and having their upper end portions inturned and oppositely disposed for directing jets of fuel upwardly and inwardly along converging lines, the outlet openings of the arms being disposed in parallel vertical plane and flared outwardly, and a hood extending around the burner tube and the air holes therein for deflecting moisture from the holes.

In testimony that I claim the foregoing as my own, I have hereto affixed my signature.

SAMUEL A. STUM.
